(57) **CLAIM**

The ornamental design for a writing instrument, as shown and described.

DESCRIPTION

FIG. 1 is a perspective view of a writing instrument, showing our new design;

FIG. 2 is a front view of the writing instrument;

FIG. 3 is a rear view of the writing instrument;

FIG. 4 is a top view of the writing instrument;

FIG. 5 is a bottom view of the writing instrument;

FIG. 6 is a left side view of the writing instrument;

FIG. 7 is a right side view of the writing instrument; and,

FIG. 8 is an enlarged bottom view of the writing instrument. The parts shown in broken lines are portions of the mechanical pencil that form no part of the claimed design.

1 Claim, 5 Drawing Sheets
